UNITED STATES PATENT OFFICE.

HENRY SIEBEN, OF KANSAS CITY, MISSOURI.

FLUID-CONTROLLING APPARATUS.

Application filed November 12, 1925. Serial No. 68,858.

My invention relates to fluid controlling apparatus and my chief object is to provide new and useful apparatus of this character whereby fluid, such, for instance, as the gas supply to a building may be manually cut off in the event of a fire, or which will automatically cut off such supply of gas in the event that certain parts of the apparatus become subjected to heat of a predetermined degree.

The invention embodies a self-closing and self-draining valve which is connected to the gas inlet pipe and normally held in open position by mechanism adapted to be actuated by a protected cable which may be run to any desired point within or without the building to enable said mechanism to be manually actuated from a distance for the purpose of closing the valve. Said mechanism also locks the valve in closed position against back pressure arising from any cause, such, for instance, as an explosion in the inlet pipe or the meter.

Other features will hereinafter appear, and in order that the invention may be fully understood reference will now be had to the accompanying drawings, in which:

Fig. 1 is a sectional view of part of a building equipped with the apparatus, a housing being broken away to show the valve in the rear thereof.

Fig. 2 is a vertical sectional view of a casing containing the mechanism for holding the valve in open and closed positions, said mechanism being shown in position to hold the valve open.

Fig. 3 is a view similar to Fig. 2, with the mechanism adjusted in position to hold the valve closed.

Fig. 4 is a detail longitudinal sectional view of the valve.

Fig. 5 is a plan view of the valve and the associate mechanism, the housing containing said mechanism being in horizontal section.

Fig. 6 is a detail of a pin which assists in holding the valve in open position.

Referring now in detail to the different parts, 2 designates the valve which is connected to the gas inlet pipe A leading from the street main B to the meter C. The lower part of the valve 2 has a raised intermediate portion 4, which being higher than the lower interior portion of the street main B and the meter, will cause any water in the valve 2 and the inlet pipe A to drain towards

said street main B, or the meter as indicated by arrows Fig. 1. Thus in cold weather there will be no water to accumulate and freeze around the valve seat 6 and prevent the valve plug 8 from completely closing. The casing of the valve 2 is also provided with a removable cap 10, so that the interior of the valve may be inspected and the valve plug 8 adjusted if necessary. The valve plug 8 is mounted at one end of an arm 12, which is fixed at its opposite end upon a rotary stem 14.

The stem 14 extends through a packing box 16 projecting laterally from the casing of the valve 2 into a housing 18 containing the mechanism for holding the valve plug 8 in open and closed positions and provided with a removable cover 19 whereby access may be had to said mechanism for the purpose of inspecting and adjusting the same.

Said mechanism in the present instance embodies a crank arm 20, a toggle joint 22, a fusible link 24, and a slotted pin 26, which latter is provided in its slotted portion with a spring detent 27 for holding it in operative position. The crank arm 20 is mounted upon the outer end of the stem 14 and connected by a pivot 28 to a link 30 of the toggle joint 22. The link 30 is connected by a pivot 32 to the companion link 34 of the toggle joint 22, said link 34 being in the form of a bell-crank mounted upon a stud 36 projecting from the adjacent side of the valve casing and coacting with the packing box 16 in holding the housing 18 firmly in position against the valve.

A coil spring 37 loosely embracing the stud 36 and having one end bearing against the packing box 16 and its opposite end against the toggle link 34, is provided for automatically closing the valve plug 8, as hereinafter described. The toggle link 34 is provided with a lug 38 to which the fusible link 24 is secured by suitable means such as a bolt 40. The free end of the fusible link 24 has an eye 42 adapted to register with a corresponding eye 43, in a lug 44 on the crank arm 20, to receive the pin 26.

The pin 26 is connected by a short cable 46 to an arm 48 formed integral with the link 34 at a point adjacent to the pivot 32.

50 designates a relatively long cable connected to the upper end of the pin 26 and running through a conduit 52 leading from the housing 18 to a weather-proof box 54,

which may be located at any desired point, but in the present instance is shown mounted upon an outer wall E of the building and within reach from the sidewalk F. The box 54 is provided with a removable front plate 55 and a lock 56, and when locked guards against unauthorized persons tampering with the handle 57 fixed to the upper end of the cable 50. The plate 55 has a lip 58 adapted to project into a groove 59 in the top of the box which projects over the plate 55 to prevent the entrance of rain, sleet, etc.

The conduit 52 may enter the rear of the box 54, as shown by Fig. 1, or it may enter an opening 60 in the bottom of said box which is provided with an antifriction roller 61 over which the cable 50 may be pulled to manually close the valve 2.

20 The elbow 62 of the conduit 52 is also provided with an antifriction roller 64 over which the cable 50 extends when the conduit is arranged as shown in Fig. 1.

In practice the valve plug 8 is held in open position by adjusting the crank arm 20 and the toggle joint 22 to the position disclosed by Fig. 2, where they are secured by the pin 26 which is passed through the registering eyes 42 and 43 in the fusible link 24 and the lug 44, respectively. Should a fire occur the box 54 is opened to give access to the handle 57, which is pulled outwardly to cause the cable 50 to withdraw the pin 26 from the registering eyes in the crank arm 20 and the fusible link 24, whereupon the spring 37 immediately operates the toggle joint so as to close the valve. Should the spring 37 get out of order and fail to close the valve, it is closed by the short cable 46 as the operator continues to pull upon the handle 57. As the valve plug 8 becomes seated further movement of the toggle joint 22 is checked by a stop 66 on the crank arm 20 contacting the upper portion of the toggle link 30, so that no damage will result to the valve plug 8 and the mechanism for holding the same open or closed should the operator continue to pull heavily upon the handle 57. As a further safeguard against the parts becoming damaged by the operator continuing to pull upon the handle 57, the upper end of the pin 26, as shown by Fig. 3, is arranged to engage the reduced portion of a nipple 68 uniting the housing 18 and the conduit 52.

Should a fire occur adjacent to the valve 2 and fuse the link 24, the spring 37 will automatically close the valve. The valve plug 8 is held in closed position by the toggle joint 22 and associate mechanism against any back pressure which may occur in the inlet pipe A between said valve plug 8 and the meter C.

65 From the foregoing description it will be understood that the cable 50, the handle

57, and the mechanism for normally holding the valve in open position are fully protected. Also by providing the housing 18 with holes 70, heat and flame will be admitted to said housing to fuse the link 24, 70 so that the valve 2 may automatically close before the heat causes the meter C to leak gas and thus cause an explosion.

While I have shown and described the preferred construction, combination and arrangement of parts I reserve the right to all such modifications thereof as properly fall within the spirit and scope of the invention as claimed.

Having thus described my invention, what I claim and desire to secure by Letters Patent, is:

1. In an apparatus of the character described, a valve, a toggle joint associated with said valve to actuate the same, a fuse which coacts with said toggle joint in holding the valve open, and spring means for operating the toggle joint to close the valve on melting of said fuse.

2. In an apparatus of the character described, a self closing valve, an arm connected to said valve, a toggle joint connected to said arm for actuating the valve, a fuse connected to said toggle joint, and means connecting said fuse and the arm for holding the toggle joint in a position to hold the valve open.

3. In an apparatus of the character described, a self closing valve, an arm connected to said valve, a toggle joint connected to said arm for actuating the valve, a fuse connected to said toggle joint, a pin connecting said fuse and the arm for holding the toggle joint in a position to hold the valve open, and means for withdrawing said pin from the fuse and arm to permit the toggle joint to move and close the valve.

4. In an apparatus of the character described, a valve, an arm connected to said valve, a toggle joint connected to said arm for actuating the valve, a link connected to said toggle joint, a pin connecting said link and the arm for holding the toggle joint in a position to hold the valve open, means for withdrawing said pin from the link and arm to permit the toggle joint to move and close the valve, and means connecting said pin and the toggle joint to cause the latter to close the valve when the former is withdrawn from the link.

5. In an apparatus of the character described, a valve, an arm connected to said valve, a toggle joint connected to said arm for actuating the valve, a fuse connected to said toggle joint, a pin connecting said fuse and the arm for holding the toggle joint in a position to hold the valve open, a cable for withdrawing said pin from the fuse and arm to permit the toggle joint to move and close the valve, and a cable connecting

said pin and the toggle joint to cause the latter to close the valve when the former is withdrawn from the fuse.

6. In an apparatus of the character described, a self closing valve, an arm connected to said valve, a toggle joint connected to said arm for actuating the valve, a fuse connected to said toggle joint, releasable means connecting said fuse and the arm for holding the toggle joint in a position to hold the valve open, and a member on the arm for checking the movement of the toggle joint when the valve closes.

7. In an apparatus of the character described, a valve, an arm connected to said valve, a toggle joint connected to said arm for actuating the valve, a fuse connected to said toggle joint, releasable means connecting said fuse and the arm for holding the toggle joint in a position to hold the valve open, and spring means engaging the toggle joint for closing the valve when said arm and fuse are released from said means or the fuse is destroyed.

25 8. In an apparatus of the character described, a self closing valve, an arm connected to said valve, a toggle joint connected to said arm for actuating the valve, a fuse connected to said toggle joint, releasable means connecting said fuse and the arm for holding the toggle joint in a position to hold the valve open, a cable connected to said means to disengage the same from the fuse and the arm so that the toggle joint may move and close the valve, and a conduit through which said cable extends.

9. In an apparatus of the character described, a self closing valve, an arm connected to said valve, a toggle joint connected to said arm for actuating the valve, a fuse connected to said toggle joint, means connecting said fuse and the arm for holding the toggle joint in a position to hold the valve open, a cable connected to said means to disengage the same from the fuse and the arm so that the toggle joint may move and close the valve, a conduit through which said cable extends, a handle connected to said cable, and a box enclosing said handle.

40 10. In an apparatus of the character described, a valve, mechanism having a tendency for closing said valve, a releasable slotted pin for securing said mechanism in position to hold the valve open, and spring means arranged in the slotted portion of said pin for holding the latter in place.

45 11. In an apparatus of the character described, a self closing valve, an arm connected to said valve, a toggle joint connected to said arm for actuating the valve, a fuse connected to said toggle joint, releasable means connecting said fuse and the arm for holding the toggle joint in a position to hold the valve open, a cable connected to said means to disengage the same from the fuse and the arm so that the toggle joint may move and close the valve, a handle connected to said cable, and a housing enclosing said toggle joint, arm and fuse.

50 55 60 65 In testimony whereof I affix my signature.

HENRY SIEBEN.
